UNITED STATES PATENT OFFICE.

MILDRED C. SCHMOLZE, OF NEW YORK, N. Y., ASSIGNOR TO FRANKLIN SIMON & CO., INC., OF NEW YORK, N. Y., A CORPORATION OF NEW YORK.

DESIGN FOR A DRESS.

Application filed October 29, 1927. Serial No. 23,927. Term of patent 3½ years.

To all whom it may concern:

Be it known that I, MILDRED C. SCHMOLZE, a citizen of the United States, and a resident of the city of New York, borough of Manhattan, in the county of New York and State of New York, have invented the new, original, and ornamental Design for Dress, of which the following is a specification.

Reference is had to the accompanying drawing, forming part thereof, wherein ing my new design, the same being illustrated on a figure indicated by dotted lines.

I claim:

The ornamental design for a dress, substantially as shown and described.

Signed at New York, in the county of New York and State of New York, this 27th day of October A. D. 1927.

MILDRED C. SCHMOLZE.
